UNITED STATES PATENT OFFICE.

THOMAS W. HURFF, OF WOODBURY, NEW JERSEY.

SMOKER'S PIPE.

1,146,259.

Specification of Letters Patent. Patented July 13, 1915.

Application filed March 30, 1914. Serial No. 828,371.

To all whom it may concern:

Be it known that I, THOMAS W. HURFF, a citizen of the United States, residing at Woodbury, in the county of Gloucester and

5 State of New Jersey, have invented certain new and useful Improvements in Smokers' Pipes, of which the following is a specification.

10 My invention relates to improvements in smokers' pipes, the object of the invention being to provide a pipe in which the smoke will be dry and cool when it reaches the mouth of the smoker.

15 A further object is to provide a pipe of this character which may be readily taken apart and easily cleaned and which when in operation will filter the smoke and prevent any saliva or moisture from reaching the filtering material, so that the latter is kept 20 in a dry condition.

25 With these and other objects in view, the invention consists in certain novel features of construction and combinations and arrangements of parts as will be more fully hereinafter described and pointed out in the claim.

30 In the accompanying drawings: Figure 1 is a view in longitudinal section illustrating my improvements. Fig. 2 is a view showing each of the separate parts of the pipe in elevation, and Fig. 3 is a view in cross section on the line 3—3 of Fig. 1.

35 1 represents the bowl of the pipe which is preferably screw-threaded at its upper end to receive a ring 2, the latter clamping a tobacco holding receptacle 4 in the bowl, so that by reason of this construction the receptacle 4 may be made of a different material from the bowl, and when in the bowl 40 will provide a smoke space 5 below the receptacle into which the smoke passes through an opening 6 in the bottom of the receptacle 4.

45 The bowl 1 has an extension 7 with a smoke passage 8 therethrough, and this extension 7, at its free end, is reduced in diameter as shown at 9 to receive a cylindrical enlargement 10 on the end of a barrel 11. This barrel 11 is adapted to contain absorbent cotton 12 or other filtering material 50 which is confined in the barrel between the end of the extension 9 and a removable plunger 13. The plunger 13 snugly fits within the barrel, and has an opening there-

through registering with the bore of a tubular stem 14 which extends beyond the end of the barrel an appreciable distance as clearly shown in Fig. 1.

55 15 represents the mouth piece of the stem, and 16 is a cylindrical casing secured to the mouth piece in any approved manner and fitting around the outside of barrel 11 with its end against the cylindrical enlargement 10, so that when the parts are assembled, the extension 7, cylindrical enlargement 10, and 60 casing 14 will be of the same external diameter to give a neat and attractive appearance to the pipe.

65 My invention is not limited to any particular material in the manufacture of the 70 different parts, nor in the manner of securing the parts together, as I may make all of the parts independent of each other or may connect some permanently.

75 In operation, the smoke from the bowl 75 passes through the passage 8, thence through the filtering material 12, thence through the tubular stem 14, and thence through the mouth piece 15. Any moisture which may flow down the mouth piece will be collected 80 in casing 16 around the outside of stem 14, the plunger 13 serving to exclude all moisture from the filtering material.

85 Whenever desired, the pipe may be readily taken apart and thoroughly cleaned, each 85 part being separately handled as shown clearly in Fig. 2.

90 Various slight changes might be made in the general form and arrangement of parts described without departing from my invention, and hence I do not limit myself to the precise details set forth, but consider myself at liberty to make such changes and alterations as fairly fall within the spirit and scope of the appended claim.

95 Having thus described my invention, what I claim as new and desire to secure by Letters Patent is:

100 A tobacco pipe comprising a hollow bowl having a screw-threaded upper end, a tobacco receptacle fitting within the bowl and projecting above the bowl, said receptacle having an opening in its lower end, a ring screwed onto the bowl and clamping the receptacle in the bowl, an extension on the 105 bowl having a smoke passage therethrough, a barrel secured to the extension and containing filtering material, a mouth piece, a

casing connecting the mouth piece and the barrel, a plunger in the barrel having an opening therethrough, and a tubular stem integral with the plunger and extending 5 into the casing beyond the end of the barrel and projecting toward the mouth piece, substantially as described.

In testimony whereof I have signed my name to this specification in the presence of two subscribing witnesses.

THOMAS W. HURFF.
